JAMES A. CARLTON, OF ST. LOUIS, MISSOURI, ASSIGNOR, BY MESNE ASSIGNMENTS, TO
CHARLES S. RUSSELL, OF WEST MEDFORD, MASSACHUSETTS.

AUTOMATIC SUCTION SHEET-FEEDING MACHINE.

Application filed September 24, 1926. Serial No. 137,440.

This invention relates to a machine for automatically successively lifting sheets of material such as paper from the top of a pile and conveying the same for any desired purpose, for example to the paper feed mechanism of a printing machine. The machine comprises in general a pick-up nozzle for lifting the top sheet from the pile by suction and means for actuating said nozzle vertically to and from the pile to pick up a sheet and horizontally to convey the sheet to the desired point.

One object of the invention is to provide a machine of this character embodying novel and improved mechanism for actuating said pick-up nozzle which is simple, reliable and inexpensive in construction and operation.

Another object is to provide in such a machine novel and improved means for separating or loosening the uppermost sheet from the pile just prior to the picking up thereof by said pick-up nozzle so that only one sheet at a time is lifted from the pile.

A further object is to provide novel and improved mechanism to cooperate with said pick-up nozzle for automatically maintaining the top of the pile at substantially a uniform elevation as by raising the pile.

Other objects are to provide a machine of the character described which can be directly driven from a printing machine, for example a multigraph machine; to provide in such a machine novel and improved suction or vacuum controlling means coordinated with the paper feed mechanism of such a printing machine whereby the suction or vacuum is relieved or broken to release the sheet from the pick-up nozzle as the printing machine mechanism grasps the sheet, and to obtain other results and advantages as may be brought out by the following description.

Referring to the accompanying drawings, in which corresponding and like parts are designated throughout the several views by the same reference characters,

Figure 1 is a side elevation of a sheet feeding machine embodying the invention, showing the same in cooperative relation to a multigraph machine for feeding sheets of paper to the latter;

Figure 2 is an end view of the upper portion of the sheet feeding machine, some parts being eliminated for clearness in illustration;

Figure 3 is an enlarged top plan view of the sheet feeding machine;

Figure 4 is an enlarged transverse vertical sectional view, taken on the line 4—4 of Figure 3;

Figure 5 is a detached fragmentary perspective view of one end of the carriage section upon which the pneumatic pick-up device is mounted;

Figure 6 is a fragmentary perspective view of one end of the bracket upon which the suction pick-up nozzles are mounted;

Figure 7 is a fragmentary perspective view of a portion of the other carriage section;

Figure 8 is a fragmentary perspective view of the forward end of the machine showing in detail the pneumatic blower, and

Figure 9 is an enlarged transverse vertical sectional view through the vacuum controlling valve.

Specifically describing the illustrated embodiment of the invention, the sheet feeding machine includes a frame A composed of two spaced and parallel vertical side pieces 1 and 2 fixedly connected together by tie-bolts 3 and a cross-bar 4, said side pieces having feet 5 for supporting the frame in upright position. This frame is adapted to be arranged in side by side relation to a multigraph machine B so that sheets of paper may be fed to the paper feed rollers C of the multigraph machine.

The stack D of the sheets of paper to be fed to the multigraph machine are supported by a table 7 mounted in the frame A between the side pieces 1 thereof for vertical movement.

At the top of the frame above the top of the stack D of sheets of paper is horizontally movable a carriage which is composed of two sections E and F which have their ends slidable in guide grooves 8 in the respective side pieces 1 and 2. The section E is shown as comprising two transverse bars 9 fast connected by end pieces 10 which are slidable in the respective grooves 8, while the section F comprises two transverse bars 11 which are connected at their ends by rack bars 12 which are also slidable in the respective grooves 8. The section F normally has an abutting relation with the section E at the forward end of the frame A, as shown in Figures 3 and 4 of the drawings; but said sections are relatively movable and are

yieldingly connected by springs 13 so as to move together. The section E has mounted thereon at its ends standards 14 on which are mounted inwardly facing vertical guide channels 15 in which are vertically slidable posts 16 which are connected by the transverse bar 17. A plurality of suction pick-up nozzles 18 are secured to the bar 17 in any suitable manner, but said nozzles are preferably adjustable longitudinally of said bar by means of bolts 20 passing through a slot 21 in the bar. The undersides of these nozzles are formed with openings 22, and the nozzles are connected by flexible tubes 23 to a manifold suction pipe 24 mounted on the frame A and extending transversely thereof and connected in any suitable manner as by a pipe 25 to a suitable vacuum producing apparatus. The posts 16 and bar 17 thus serve as a bracket or hanger for the suction pick-up nozzles 18.

Upon the posts 16 are mounted inwardly and horizontally projecting rollers 26 which follow respective cams 27 secured to the other frame section F, as shown in Figure 7 of the drawings. These cams 27 project forwardly from the section F in overlying relation to the section E so as to be always beneath the respective rollers 26. With this construction, it will be observed that the suction pick-up nozzles 18 will be moved by the carriage horizontally toward and from the stack D of the sheets of paper and may move vertically to and from the top sheet of said stack by longitudinal movement of the cams 27 beneath the rollers 26 which of course can take place only upon relative movement of the frame sections E and F.

For moving the carriage, I have shown a transverse shaft 30 journaled on the frame A and having thereon pinions 31 meshing with the respective rack bars 12, said shaft having at one end thereof another pinion 32 which meshes with another rack bar 33 horizontally reciprocable on the outside of the frame piece 1 in suitable bearings or guides 34. A lever 35 is pivotally mounted at one end upon a stub shaft 36 on the outside of said frame piece 1 and the other end of said lever is pivotally connected at 37 to the rack bar 33. A link 38 has one end connected to the lever 35 intermediate its ends and the other end connected to a crank 39 on a rotating shaft 40 commonly found in known types of multigraph machines, particularly those which are power driven. This shaft 40 constantly rotates during operation of the multigraph machine as accordingly does the crank 39. Thus, during operation of the multigraph, the lever 34 is constantly oscillated alternately in opposite directions and through the rack bar 33, pinion 32, pinions 31 and the rack bars 12 reciprocates the carriage alternately in opposite directions.

In accordance with the invention, to cause

vertical movement of the suction pick-up nozzles 18, when the two sections E and F of the carriage have moved a certain distance together away from the multigraph machine, the standards 14 engage abutment lugs 41 mounted on the frame A of the machine, as shown in Figures 3 and 4, so that movement of the carriage section E is interrupted. The carriage section F continues to move in the same direction to the limit of its movement determined by the extent of movement of the lever 35, and during this continued movement against the influence of the springs 13, the cams 27 are partially withdrawn from beneath the rollers 26 so that the nozzles 18 move vertically by gravity into engagement with the top sheet in the stack D. Upon a reverse in the direction of the movement of the carriage section F, the springs 13 still maintain the section E stationary and the cams 27 are thus pushed forwardly beneath the rollers 26 so that the nozzles 18 are vertically raised from the stack. When the section F abuts the section E, the two sections move together toward the multigraph machine with the nozzles 18 elevated above the stack. Due to the suction or partial vacuum in the nozzles 18 when they contact with the top sheet in the stack D, the said sheet is picked up by the nozzles and carried therewith. The extent of movement of the nozzles and their elevation will of course correspond to the location of the paper feed roller C of the multigraph machine, so that at the limit of forward movement of the nozzles the edge of the sheet is directed between the said rollers.

The invention also contemplates a blower for separating the uppermost sheets of the stack to prevent more than one sheet being lifted at a time. This blower is shown as comprising a manifold pipe 50 extending transversely of the frame at the forward edge of the stack D and rotatably journaled in the frame, said manifold having a plurality of nozzles 51 directed toward the stack. The manifold is connected to a source of compressed air, for example the exhaust of the vacuum producing apparatus, so that the current of air is constantly directed toward the sheets in the stack.

In accordance with the invention, this manifold is oscillated to move the nozzles 51 upwardly as the pick-up nozzles 18 approach the stack, and for this purpose I have shown a crank arm 52 connected to one end of the manifold and being in turn connected by a link 53 to a crank arm 54 mounted on a stub shaft 55 journaled in the frame piece 2. An arm 56 projects upwardly from the end of the stub shaft 55 at the inside of the frame piece so as to be in the path of movement of the carriage section F when the latter approaches the limit of its movement. The nozzles 51 are normally influ-

enced downwardly by a tension spring 57. With this construction it will be obvious that each time the frame section F engages the arm 56, the nozzles 51 will be swung upwardly so that the currents of air issuing therefrom will separate the uppermost sheets of paper and facilitate the picking up of the top sheet by the pick-up nozzles 18, and when the carriage section moves in the other direction the nozzles 51 are moved downwardly so as to cause no disturbance of the uppermost sheets.

It is also a feature of the invention to provide means for automatically elevating the pile to compensate for the removal of sheets from the top thereof by the nozzles 18 so as to maintain the top of the pile at a uniform level. For this purpose, I have shown a ratchet or gear 60 secured to the stub shaft 36, and a pawl 61 pivotally mounted intermediate its ends upon the lever 35 so as to by action of gravity be normally out of engagement with said gear or ratchet. The gear 60 meshes with a pinion 62 on a countershaft 63 journaled on the cross-bar 4 and having a beveled pinion 64 meshing with another beveled pinion 65 which is interiorly threaded and through which passes a threaded rod 66 the end of which is connected at 67 with the table 7. For forcing the pawl 61 into engagement with the gear 60, I may utilize a push lever 68 pivotally mounted intermediate its ends as at 69 upon the frame piece 1 with one end bearing upon the toothed end of the pawl 61 and the other end connected by a link 70 to an arm 71 on a transverse shaft 72 extending across the frame A above the top of the stack. A feeler arm 73 is mounted on the shaft 72 and by action of gravity normally rests upon the top sheet of the stack D oscillating the shaft 72 accordingly. With this construction, it will be obvious that when the top of the pile reaches a predetermined low level, the oscillation of the feeler arm 73 will move the push lever 68 so as to force the pawl 61 into engagement with the gear 60, and oscillation of the lever 35 will then cause rotation of the gear 60, pinion 62, shaft 63 and pinions 64 and 65 so that the threaded rod 66 is moved upwardly; and when the top of the pile reaches a predetermined high level, the pawl 61 will be released from the gear 60 and movement of the table 7 will be interrupted. For lowering the table 7 to replenish the stack, the gear 60 may be provided with a handle 74 whereby the pinions 62, 64 and 65 may be quickly and manually rotated to quickly lower the table.

It is desirable to diminish or break the vacuum in the nozzle 18 after the sheet of paper carried thereby is gripped by the feed roller C, and accordingly I may connect an air inlet valve 75 with the nozzles in the

vacuum system through a pipe 76 which will admit air to the system and break or diminish the vacuum. This valve may include a casing 77 having a seat 78 communicating with the atmosphere through a passage 79, and a valve head 80 carried by a valve rod 81 projecting upwardly through said passage. The valve 80 is normally held in closed position by a compression spring 82. A cam 83 is mounted on the link 38 so that as the link moves downwardly incident to its actuation by the shaft 40 to move the nozzle 18 forwardly, said cam 83 presses on the valve rod 81 so as to open the valve 80, as shown in Figure 9 of the drawings. Obviously, this engagement of the cam 83 with the valve rod will be momentary due to the oscillation of the link as the crank arm 39 moves upward.

While I have shown and described the invention as embodied in certain details of construction and as used in connection with a multigraph machine, it will be understood that this is primarily for the purpose of illustrating the principles of the invention and that the details of construction may be modified and changed and the machine adapted for feeding sheets of material for other purposes, without departing from the spirit or scope of the invention. Therefore, I do not desire to be understood as limiting myself except as required by the following claims when construed in the light of the prior art.

Having thus described the invention, what I claim is:

1. A sheet feeding mechanism, comprising a support for a stack of sheets, a carriage horizontally movable above said stack and comprising two sections movable independently and together, a pneumatic device for lifting the top sheet from said stack mounted to move vertically on one of said carriage sections, and means for vertically moving said pneumatic device alternately in opposite directions upon relative movement in opposite directions of said carriage sections, whereby the top sheet on said stack is successively lifted from said stack and horizontally moved away therefrom.

2. A sheet feeding mechanism, comprising a support for a stack of sheets, a carriage horizontally movable above said stack and comprising two sections movable independently and together, a pneumatic device for lifting the top sheet from said stack mounted to move vertically on one of said carriage sections, means for moving said carriage, means for temporarily stopping movement of the first-mentioned carriage section with the other, and means on the other carriage section to vertically move said pneumatic device alternately in opposite directions upon relative movement of said carriage sections in opposite direction.

3. A sheet feeding mechanism, comprising a support for a stack of sheets, a carriage horizontally movable above said stack and comprising two sections movable independently and together, a pneumatic device for lifting the top sheet from said stack mounted to move vertically on one of said carriage sections, a cam and a follower therefor, one thereof being connected to 10 said pneumatic device and the other to the other carriage section for moving said pneumatic device vertically alternately in opposite directions upon relative movement in opposite directions of said carriage sections, 15 whereby the top sheet on said stack is successively lifted from said stack and horizontally moved away therefrom.

4. A sheet feeding mechanism, comprising a support for a stack of sheets, a carriage horizontally movable above said stack and comprising two sections movable independently and together, a pneumatic device for lifting the top sheet from said stack mounted to move vertically on one of said carriage sections, means for moving said carriage, means for temporarily stopping movement of the first-mentioned carriage section with the other, a cam and a follower therefor, one thereof being connected to 20 said pneumatic device and the other to the other carriage section for moving said pneumatic device vertically alternately in opposite directions upon relative movement in opposite directions of said carriage sections, 25 whereby the top sheet on said stack is successively lifted from said stack and horizontally moved away therefrom.

5. A sheet feeding mechanism, comprising a support for a stack of sheets, a carriage horizontally movable above said stack and comprising two sections, means yieldably connecting said sections so that they may move together and also move relatively to each other, a pneumatic device for picking up the top sheet from said stack mounted on one of said sections, means connected to the other section for horizontally moving it, means for interrupting movement of the first-mentioned section with the other in one direction whereby the second-mentioned section may have limited movement independently of the first-mentioned section in both directions, and means for vertically moving said pneumatic device alternately in opposite directions upon relative movement in opposite directions of said carriage sections, 50 whereby the top sheet on said stack is successively lifted from said stack and horizontally moved away therefrom.

6. A sheet feeding mechanism, comprising a support for a stack of sheets, a carriage horizontally movable above said stack and comprising two sections, means yieldably connecting said sections so that they may move together and also move rela-

tively to each other, a pneumatic device for picking up the top sheet from said stack mounted on one of said sections, means connected to the other section for horizontally moving it, means for interrupting movement 70 of the first-mentioned section with the other in one direction whereby the second-mentioned section may have limited movement independently of the first-mentioned section in both directions, a cam and a follower 75 therefor, one thereof being connected to said pneumatic device and the other to said second-mentioned carriage section for moving said pneumatic device alternately in opposite directions upon relative movement in 80 opposite directions of said carriage sections, whereby the top sheet on said stack is successively lifted from said stack and horizontally moved away therefrom.

7. The combination with a machine for operating upon sheets including a rotating shaft having a crank arm, of a sheet feeding mechanism comprising a frame, a support for a stack of sheets to be fed to said machine, a device for picking up the top sheet 90 from said stack and horizontally movable from said stack to said machine to convey said sheet to said machine, a lever pivoted on said frame for oscillation in a vertical plane at right angles to the axis of said shaft, a link connected to said lever and said crank arm on said shaft whereby rotation of said shaft oscillates said lever, and an operative connection between said lever and said sheet lifting device for moving the latter alternately in opposite directions.

8. The combination with a machine for operating upon sheets including a rotating shaft having a crank arm, of a sheet feeding mechanism comprising a frame, a support 105 for a stack of sheets to be fed to said machine, a device for picking up the top sheet from said stack and horizontally movable from said stack to said machine to convey said sheet to said machine, a lever pivoted on said frame for oscillation in a vertical plane at right angles to the axis of said shaft, a link connected to said lever and said crank arm on said shaft whereby rotation of said shaft oscillates said lever, a 110 rack bar horizontally reciprocable in said frame and connected to said sheet lifting device, and an operative connection between said lever and said rack bar for moving the latter alternately in opposite directions.

9. The combination with a machine for operating upon sheets including a rotating shaft having a crank arm, of a sheet feeding mechanism comprising a frame, a support 115 for a stack of sheets to be fed to said machine, a device for picking up the top sheet from said stack and horizontally movable from said stack to said machine to convey said sheet to said machine, a lever pivoted on said frame for oscillation in a vertical 120 plane at right angles to the axis of said shaft, a link connected to said lever and said crank arm on said shaft whereby rotation of said shaft oscillates said lever, a 125 rack bar horizontally reciprocable in said frame and connected to said sheet lifting device, and an operative connection between said lever and said rack bar for moving the latter alternately in opposite directions.

plane at right angles to the axis of said shaft, a link connected to said lever and said crank arm on said shaft whereby rotation of said shaft oscillates said lever, a rack 5 bar horizontally reciprocable in said frame and connected to said sheet lifting device, a shaft journaled on said frame, a pinion on said shaft meshing with said rack bar, a second pinion on said shaft, a second rack 10 bar horizontally reciprocable on said frame and meshing with said second pinion, and an operative connection between said second rack bar and said lever for moving the latter alternately in opposite directions.

15 10. The mechanism set forth in claim 1 with the addition of a pneumatic blower for directing a current of air against the edges of the uppermost sheets in said stack to separate said stack, said pneumatic blower 20 being mounted to oscillate about a horizontal axis, and means for oscillating said pneumatic blower upwardly and downwardly simultaneously with the movement of said sheet lifting means to or from said stack 25 respectively.

11. The mechanism set forth in claim 1 with the addition of a pneumatic blower for directing a current of air against the edges

of the uppermost sheets in said stack to separate said stack, said pneumatic blower 30 being mounted to oscillate about a horizontal axis, and means actuated by said carriage for moving said pneumatic blower upwardly as said pneumatic pick up device moves vertically toward said stack.

35

12. The mechanism set forth in claim 1 with the addition of a pneumatic blower for directing a current of air against the edges of the uppermost sheets in said stack to separate said stack, said pneumatic blower 40 being mounted to oscillate about a horizontal axis, and means actuated by the second-mentioned carriage section as it moves relatively to the first-mentioned carriage section for moving said pneumatic blower 45 upwardly.

13. The combination set forth in claim 7 wherein said device for picking up a sheet from said stack is a suction device, and with the addition of a normally closed air 50 inlet valve connected to said suction device and actuated by said link to admit air into said suction device for releasing said sheet therefrom.

JAMES A. CARLTON.
